CLAIM

The ornamental design for a display screen with graphical user interface, as shown and described.

DESCRIPTION

FIG. 1 is a front view of a first embodiment of a display screen with graphical user interface, showing our new design;

FIG. 2 is another front view of a second embodiment of a display screen with graphical user interface, showing our new design;

FIG. 3 is another front view of a third embodiment of a display screen with graphical user interface, showing our new design;

FIG. 4 is a front view of a fourth embodiment of a display screen with graphical user interface, showing our new design;

FIG. 5 is another front view of a fifth embodiment of a graphical user interface for a display screen, showing our new design; and,

FIG. 6 is another front view of a sixth embodiment of a graphical user interface for a display screen, showing our new design.

The broken lines illustrate the display screen and form no part of the claimed design. The broken lines illustrate portions of the graphical user interface and form no part of the claimed design.

1 Claim, 6 Drawing Sheets
